CLAIM

The ornamental design for an electronic atomizing device, as shown and described.

DESCRIPTION

FIG. 1 is a perspective view of an electronic atomizing device according to my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a perspective view of the electronic atomizing device of FIG. 2 in a state of use;

FIG. 10 is a perspective view of the electronic atomizing device of FIG. 2 in another state of use; and,

FIG. 11 is another perspective of the electronic atomizing device of FIG. 1 in the state of use.

The broken lines in the drawings depict portions of the electronic atomizing device that form no part of the claimed design.
